(57) **CLAIM**

The ornamental design for a fenestration hinge, as shown and described.

DESCRIPTION

FIG. 1 is a first perspective view of the fenestration hinge, showing the new design.

FIG. 2 is a second perspective view of the fenestration hinge of FIG. 1.

FIG. 3 is a third perspective view of the fenestration hinge of FIG. 1.

FIG. 4 is a front view of the fenestration hinge of FIG. 1. FIG. 5 is a back view of the fenestration hinge of FIG. 1. FIG. 6 is a first side view of the fenestration hinge of FIG. 1.

FIG. 7 is a second side view of the fenestration hinge of FIG. 1.

FIG. 8 is a top view of the fenestration hinge of FIG. 1.

FIG. 9 is a bottom view of the fenestration hinge of FIG. 1. FIG. 10 is a fourth perspective view of the fenestration hinge of FIG. 1 installed in an example fenestration assembly.

FIG. 11 is an enlarged fifth perspective view of the fenestration hinge taken from the area labeled “11” on FIG. 10; and,

FIG. 12 is a sixth perspective view thereof.

The broken lines depict environmental or unclaimed subject matter only and form no part of the claimed design.

1 Claim, 9 Drawing Sheets
